(57) **CLAIM**

The ornamental design for a tunnel shaped display, as shown and described.

DESCRIPTION

FIG. 1 is a perspective view of a tunnel shaped display showing our new design;

FIG. 2 is a front elevation view thereof, FIG. 2 also indicating a section view that is further shown in FIG. 7;

FIG. 3 is a left elevation view thereof;

FIG. 4 is a right elevation view thereof;

FIG. 5 is a top plan view thereof;

FIG. 6 is a bottom plan view thereof;

FIG. 7 is a section view of the interior of the tunnel shaped display, the direction of the section view corresponding to what is indicated in FIG. 2.

FIG. 8 is a view of the same section view as shown in FIG. 7. In this view the tunnel shaped display is displaying content comprising a static image. The displayed content, shown in dashed lines, is for illustrative purposes and forms no part of the claimed design.

FIG. 9 is another view of the same section view as shown in FIG. 7. In this view the tunnel shaped display is displaying content comprising an animated or moving image. The displayed content, shown in dashed lines, is for illustrative purposes and forms no part of the claimed design; and,

FIG. 10 is a perspective view of a second embodiment of our tunnel shaped display. The outline of a person standing in the interior of the tunnel shaped display, shown in dashed lines, is for illustrative purposes and forms no part of the claimed design.

The claimed tunnel shaped display has a curved viewing plane visible on the interior of a tunnel like shape large enough for a person to walk through and view.

The back elevation view is a mirror image of the front elevation view of FIG. 2.

The broken away symbols indicate that any portion beyond what is shown forms no part of the claim.

Any broken lines and any dashed lines of FIG. 1 through FIG. 10 not previously described are for illustrative purposes only and form no part of the claimed design.

1 Claim, 9 Drawing Sheets
